UNITED STATES PATENT OFFICE.

JOHN D. PEDERSEN, OF JACKSON, WYOMING.

FIREARM.

1,355,423.

Specification of Letters Patent. Patented Oct. 12, 1920.

Application filed October 22, 1919. Serial No. 332,393.

To all whom it may concern:

Be it known that I, JOHN D. PEDERSEN, a citizen of the United States, residing in Jackson, in the county of Lincoln and 5 State of Wyoming, have invented certain new and useful Improvements in Firearms, of which the following is a specification.

This invention relates to that class of firearms in which the barrel is without longitudinal movement relative to the frame, but is detachably united thereto, and relates more especially to small-arms in which the sliding bolt-carrier or breech block thereof is arranged for being locked in retracted 15 or "open" position by means of a slide-lock actuatable into a slide-engaging position by a spring-actuated magazine follower.

My present improvements are especially applicable to those kinds of small-arms 20 which are provided with magazines having spring-actuated followers, or cartridge-feeders, and particularly to that class of these small-arms which are commonly known as auto-loading pistols.

25 In a copending allowed application Serial No. 209,485, filed December 29, 1917, I have described an improvement as applied to an auto-loading pistol, whereby the barrel is detachably united with the frame by means 30 of a transverse bar or "cross-shaft", which in addition to directly uniting the barrel to the frame, is also directly coactive with the breech-slide for holding in place and releasing this barrel-holding bar; and, 35 whereby such a cross-bar,—having the form of a shaft,—is combined with a slide-lock or stop-arm member which may be continuously subjected to a frictional regulation or control by a force derived and transmitted 40 from the breech-slide-actuating spring. My present invention is in the nature of an improvement on the mechanism illustrated in said prior application.

A principal object of the present invention 45 is to furnish an improved mechanism or device of the class specified, in which a barrel-and-frame-uniting cross-bar shall be operatively combined with a separate member that is a combined follower-actuatable 50 slide-lock and cross-bar-rotating lever. A further object is to so organize and arrange such a combined device that each one of said members thereof shall be removable from the firearm while the other one remains

in working position; also, to accomplish this 55 result by a combination of devices which shall require only a single bore in, or through, the frame of the firearm, and which, preferably, shall permit this bore to be cylindrical and of a uniform size 60 throughout the length thereof. Further objects and advantages are hereinafter pointed out and explained.

In the accompanying drawing forming a part of this specification, my present improvements are illustrated as applied to an auto-loading pistol of which only the upper portion is shown, but sufficient for illustrating the arrangement and mode of operation of the features and devices hereinafter described.

Figure 1 is a side view or elevation of the upper portion of an auto-loading pistol having my present improvements applied thereto in a preferred form and arrangement thereof; in this view the "bolt-carrier", or breech-slide, S, is shown in its forward or firing position, on the frame F.

Fig. 2 is a side elevation similar to and drawn in alinement with and below Fig. 1, 80 but showing the breech-slide retracted to about the usual loading position; in this view the slide S is shown locked in its retracted position by the slide-stop arm d, as hereinafter more fully explained.

Fig. 3 is a longitudinal section for illustrating the arrangement of the shaft-form cross-bar, C, whereby the barrel and frame are detachably united.

Fig. 4 is a partial plan view drawn on an 90 enlarged scale and with some portions broken away or shown in section, for illustrating the preferred arrangement of the principal coacting members.

Fig. 5 is a cross-sectional view in line X⁵, 95 Fig. 3, for illustrating said barrel-and-frame-connecting cross-bar, C, in a side view thereof; this view is drawn on a scale corresponding to Fig. 4.

The detail views Figs. 6, 7 and 8, are 100 respectively, a plan view, side view and an end view of the form of rotatable cross-bar, or shaft, shown in Figs. 1 to 5, inclusive.

The detail views Figs. 9 and 10, are 105 respectively, a plan view, (as in Fig. 4), and a side view, (as in Figs. 1, 2), of the slide-lock member, or lever d; and, Fig. 11 is a cross-sectional view in line X¹¹ of Fig. 10.

Figs. 12 and 13 are fragmentary side views, (the latter corresponding to a mid-portion of Fig. 1), for illustrating certain features of the operation of the mechanism, 5 as hereinafter described.

Fig. 14 is a sectional plan view, similar to a portion of Fig. 4, for illustrating a modification as regards the detail construction of the cross-shaft and slide-lock members. 10

Fig. 15 is an end view of the cross-shaft member as seen from the left-hand in Fig. 14; Fig. 15^a is an end view of said member as seen from the right-hand in Fig. 15; 15 Fig. 15^b is an end view of the slide-lock member as seen from the left-hand in Fig. 14; and, Fig. 15^c is a side view of said slide-lock member as seen from below in Fig. 14.

Fig. 16 is a side elevation and Fig. 16^a is 20 a sectional plan view (similar to Fig. 14), for illustrating a further modification as regards the coactive relations of the members C and d.

Fig. 17 is a sectional view (similar to Fig. 25 5) taken about in line X¹⁷ of Fig. 16, for further illustrating the modified construction shown in Figs. 16 and 16^a; and, Fig. 17^a is a side view (as in Fig. 16) of the form of slide-lock member shown in Figs. 30 16, 16^a, and 17.

Fig. 18 is a sectional view similar to Fig. 17, but showing certain details more fully in section, and showing a construction in which the slide-lock member is not adapted 35 for turning the cross-shaft member; and, Fig. 18^a is a side view of said slide-lock member of Fig. 18, as seen from the right-hand in said Fig. 18.

Fig. 19 is a sectional plan view (resembling 40 a portion of Fig. 4) for illustrating a further modification as to certain features of the firearm mechanism; Fig. 20 is a cross-sectional view thereof, (corresponding in part with Fig. 5); and, Fig. 20^a is a side view of the slide-lock device of Fig. 19 as 45 seen from below in Fig. 19 and from the right-hand in said Fig. 20.

Fig. 21 is a fragmentary side view, and Fig. 22 a sectional plan view, (on a larger 50 scale and analogous to Figs. 4, 14, and 19), for illustrating a further modification of the mechanism which is hereinafter more fully explained; Fig. 22^a is a detail view,—in side elevation,—of the form of slide-lock device shown in Figs. 21 and 22, and is shown 55 as if seen from below in Fig. 22.

Similar characters designate like parts in all the views.

In the drawing, F is the upper portion of 60 the frame or "receiver" of an auto-loading pistol of the class to which my present invention is applicable. This frame-member in practice, may be made of any suitable design and proportions, and the particular 65 design, F, shown herein, has been selected

merely for the purposes of illustration, and because it may be considered as typical of various other such frames which are already well-known in this art.

The bolt-carrying breech-slide,—designated in a general way by S,—is shown slidably mounted on the frame F in a well-known manner by means of the usual kind of interengaging ribs and grooves; these are clearly shown in the sectional view, Fig. 5, 75 and being already common in the art, do not require a particular description. The slide is retractable on the frame,—as usual in this class of firearms,—through a loading stroke from a firing to a loading position, and it is 80 provided with a lock-face on the side thereof of which is adjacent to a slide-locking stop-arm, as hereinafter more fully explained.

The forward portion of the slide S, (at the left-hand in Figs. 1 and 2), is shown 85 formed with an interior barrel chamber, 3^a, and as having in section, (Fig. 5), a customary inverted U-shape, so that the slide, at the section indicated, may be said to have,—to be made up of,—a top-wall, as 3^b, (usually 90 curved about as shown), and the two depending side-walls, 3^c, 3^{c'}, which extend downwardly to a position somewhat lower than the bore of the barrel. In each of these side-walls, in this instance, there is 95 formed a recess or gate-way, for a purpose hereinafter explained; in the wall 3^c, the recess is designated by 2, and the one in wall 3^{c'}, (Fig. 12), by 2'. Also, the slide may be said to be provided on one side-wall 100 thereof, as 3^e, with a lock-face 3^{k'} while the opposite side-wall thereof, 3^{c'}, has therein said recess 2', in position for acting as a shaft-releasing means.

The barrel is designated in a general way 105 by B, and is shown inclosed within the slide-chamber 3^a, (Figs. 3, 4, 5), excepting that the forward end, 2^a, (shown in Fig. 2, shortened by the breaking away of a portion), is shown slidably supported in a well-known 110 manner in a ring or bearing, 3^d, which is removably fixed in the forward end of said slide member, so that said end-portion 2^a may be said to extend outwardly, in a forward direction, from said chamber 3^a; this 115 feature of the barrel-mounting is also illustrated in my aforesaid prior application. The temporary removal of said ring 3^d, also facilitates the preliminary assembling of the slide and barrel, as will be readily understood. The rear end, 2^b, of the barrel B is shown enlarged to nearly fill, transversely, said chamber 3^a, and thus also to form at 2^c, a shoulder, between which and said bearing 3^d, the slide-actuating spring, N, is held 120 under suitable compression.

In the system as thus far described, or organizing the three principal members of an auto-loading pistol, it is contemplated that,—for the purposes of my present im- 130

provements,—the barrel at the rearward end thereof will be supported and releasably retained in position by an interlock-connection directly with the frame. It is also desirable, obviously, so to unite the barrel and frame that the rearward end of the barrel can have no movement,—nor any material amount of "play",—transversely of the frame either laterally or vertically.

When the slide S has the usual upper wall, (as indicated for instance, at 3^b, Fig. 3), of course, the barrel B will be covered or "housed" in by said slide-wall. However, the rear end 2^b of the barrel, is preferably so reduced in size relative to said chamber space within the slide, as not to actually bear against the inner surface of said slide-wall,—thus avoiding the possibility of any undue friction as between the barrel and the moving slide. When said parts are thus arranged and properly fitted, a slight space will be formed between the slide-walls and barrel-end 2^b, as indicated at 3^e, (Figs. 3 and 5), where,—in accordance with a conventional practice,—the very small amount of space actually or normally required is shown somewhat enlarged to secure clearness of illustration.

For releasably and directly connecting the barrel with the frame, these members are provided with interengaging portions of the nature of an interlock device. Accordingly, as one suitable form thereof, the frame F is herein shown having formed therein the recess a³, (see Figs. 3 and 5), and the barrel B is shown provided near the rearward end thereof with a downward extension b', which in practice may have any convenient form suitable for the particular size and shape of said recess. Said depending portion of the barrel should, of course, be fitted rather closely between the side walls of said recess so that the rearward end of the barrel will be held in place with a proper degree of rigidity.

When the barrel is put in place on the frame, these two members are then strongly but releasably united by means of a transverse bar, as C, which is of the nature of a cross-shaft, and for the present purposes is made circular in section, so that it may be turned in its seats, as a⁴, a^{4'}, in the frame. The transverse member C, being thus seated in the frame and passing through said barrel projection, is thereby adapted for directly taking the recoil force of the barrel after the manner of a beam which is supported at each end thereof and has a heavy pressure applied thereto about mid-way of its length and in a direction transverse thereto. Said shaft-seats a⁴, a^{4'}, together form a single "shaft seat" which is located transversely of the firearm, and which extends through the frame and is herein shown positioned partly above and partly

below the plane of the lower edges of said side walls of the slide. Said lower edge portions of the walls 3, 3', therefore, in this instance, have inner surfaces, or faces, constituting one form of bar-retaining or "shaft-retaining" means,—also stop-arm-retaining means,—appurtenant to the slide, and which are arranged for separately and releasably retaining in working position said shaft and stop-arm, and for permitting each to be disassembled from the firearm independently of the other.

Said shaft member C, in order that it may have a full support upon the frame, is shown in the drawing (Figs. 4, 5, 14, 16) as extending through the frame-bearing a⁴, and barrel-projection or lug B', and part of the way through the frame-bearing a^{4'}. This arrangement provides for the inner end of the arm-hub a⁴ to be supported or journaled in the outer portion of said bearing a⁴, so that the arm d is or may be adapted to be journaled in that end of said shaft-seat which is on the same side of the firearm as said lock-face with which the stop-arm coacts, and on the side which is opposite to the shaft-withdrawal side of the frame. Thus the member d is shown in one form thereof as being pivotally supported at one end in the frame; but in the modified arrangement shown in Fig. 16, such is not the case.

The slide-lock, or stop-arm, is designated in a general way by d; it has a lock-end,—as 4^a, Fig. 10,—which is a lock-face-engaging device, and is in position for coacting with the lock-face 3^a of the slide S, when the latter member is in one retracted position. When the arm d is provided with a hub, as d⁴, this may be held properly in place as shown in Fig. 5 where the hub is shown reduced on its upper side to form the faces d⁶ and d^{6'} so that this face, d⁶, will engage or be coactive with the inner face 3^h, this being a shaft-retaining means appurtenant to the slide wall 3^e; the surface d⁶ should, of course, be made low enough to sufficiently clear the lower edge, 3^t, of said slide-wall.

Similarly, the outer end c⁵ of the shaft C is shown reduced to form the two faces c² and c⁶, of which the latter one is an outwardly-facing transverse face that engages or coacts with the inner surface, 3^{h'}, of the slide-wall 3^e, while the surface c² is made low enough to permit said shaft to have the necessary amount of rotative movement. Thus the two members C and d are herein shown normally but separately retained in place,—except in Figs. 16, 17,—each by a similar means, but located, respectively, on opposite sides of the frame.

On account of the described arrangement of the member C, it will be evident from the drawing that as regards the sustaining

of the forces transversely-applied thereto, said cross-shaft does not have imparted thereto any turning movement or tendency to rotate, and does not have in the assembled mechanism the function of a pivot in relation to any of the members, since the barrel alone is separably supported thereon, and since the barrel has no turning or other movement with relation to the cross-bar or to the frame during the operation of the slide.

The cross-shaft C is herein shown provided with an enlarged end, or head-portion, as c^4 , the inner face c^7 of which comes 5 against the surface of the frame F, thereby holding the shaft against longitudinal movement in one direction. Outward movement is similarly prevented by the aforesaid transverse surface c^6 of the shaft engag- 10 gaging the inner surface 3^8 of the slide-wall 3^8 ; thus the cross-shaft is provided with the two oppositely-disposed movement-limiting surfaces, as c^6 and c^7 , for releasably holding the shaft in working position 15 relative to the frame and breech-slide, and for preventing a shaft-withdrawal movement, excepting when the shaft-releasing recess is brought into position therefor.

On account of the usual mode of taking 20 the pistol in hand, it will usually be desirable to locate the cross-shaft with the head c^4 thereof at the right-hand side of the pistol frame and this, it will be understood, is the arrangement herein illustrated. 25 However, it will be evident that said arrangement may be reversed, if desired or should occasion require, so as to bring the head of the cross-bar at the right-hand side of the frame; in this case, of course, the 30 arm d would be located on the right-hand side,—but this reversed arrangement is not herein shown.

In order to provide for the inserting and 35 withdrawing of said cross-shaft C when constructed and positioned as herein explained, one of the side-walls of the slide, (in this instance, the right-hand wall 3^8), has a recess, as $2'$, (Fig. 12), in such a position 40 therein that when the slide is at some convenient point between the ends of its travel, or working stroke, this recess will come into alinement with said cross-shaft seat a^4 , of the frame, and thereby permit 45 said shaft to be pushed out through said recess as through a door or gate-way therefor. Thus the shaft-holding face of said 50 side-wall 3^8 , may be said to have the continuity thereof interrupted at a position for permitting the withdrawal of the body of 55 the cross-shaft C outwardly from said shaft-seat when the slide is in one position thereof.

In practice, the gate-way spaces, 2 and $2'$, should be so located as not to be in alinement with the cross-shaft when the slide S 60 is being held in a fully retracted position

(Fig. 2), and so that the user, when desiring to take out the cross-shaft, will be required to draw back the slide for only a short distance. This arrangement,—as shown in Figs. 1 and 2,—also has the advantage that 70 in the normal operation of the firearm, said gate-way recesses 2 and $2'$, will pass the cross-shaft C and arm hub d^4 , respectively, while moving at a high velocity, thereby safeguarding the operation. A further safe- 75 guard is also secured, since the force of the spring N, and the action of the recoil, ap-plies pressure to the cross-shaft C during the time the recess 2 is passing this shaft, and thus tends to hold the shaft so firmly 80 as to prevent any longitudinal movement thereof during such a brief time-interval.

In my present improvements, as will now be evident, the cross-shaft member C does not need to be turned preliminarily to the 85 withdrawal thereof, but when the slide, S, is moved to bring the recess or gate-way $2'$ into alinement with said member C, (see Fig. 12), this member may then be drawn directly outward toward the left-hand in 90 Fig. 5; this operation frees the barrel and the frame each from the other, except as to the engagement of the aforesaid depending part of the barrel within the recess or mortise of the frame. That outward movement, 95 however, of said cross-shaft is effectually prevented at all times during the normal operation of the firearm, because then the sliding bolt-carrier S is always moving either forwardly or rearwardly whenever said 100 gate-way $2'$ is at or adjacent to said cross-shaft member.

The barrel-and-frame uniting cross-shaft, as C, is coactively connected with, or coupled to, the structurally separate slide-stop 105 member, as stop-arm d , in a releasable manner, so that said shaft C may be turned by the swinging movement of said stop or arm, d , while friction applied to said shaft member will resist in some measure that movement of said arm d . A preferred way of effecting such coactive coupling, is by a construction illustrated in Figs. 1 to 11, inclusive. In this form of the present improvement, the shaft C is provided with an extension or stem, c^5 , (Figs. 6-8), and this is shown of a polygonal shape,—preferably a square, a 110 illustrated,—and is fitted to closely but slidably engage with the similarly-shaped hole or socket, d^5 , (Figs. 9-11), of the stop-arm 115 member d . Thus the hub portion, d^4 , of said arm d fits upon said projection c^5 in such a manner that the arm d may be said to constitute a crank-arm or lever, whereby 120 to turn said shaft C. This same form of the inter-engagement of the members C and d is also applicable to,—and is herein shown employed in,—the modified construction and arrangement illustrated in Figs. 16 and 17, but here a different arm-retaining means is 125 130

employed, as hereinafter more fully explained. A different specific form, however, of the said coupling means, is illustrated in Figs. 14 and 15.

5 In some instances, if preferred, the recesses 2 and 2' may be located on the same transverse line, (not herein shown), so that with the slide S in one position, the shaft C may be first withdrawn through the recess 2', and then the slide-lock d be withdrawn by passing the hub portion d⁴ thereof outwardly through the recess 2; of course, this order of withdrawal may be reversed when the two said recesses are located in 10 alinement as here explained; or, the two parts C and d may be withdrawn simultaneously, the one toward the right-hand and the other toward the left-hand. This mode of action, however, is deemed to be objectionable in some firearms, and therefore I prefer the arrangement of said recesses or gate-way spaces herein illustrated, in which one said space, as 2' is located somewhat farther back in the slide S, than is the recess 2. By means of this construction, when the slide is drawn back a short distance from its firing-position, the member C may be drawn out at one side of the slide and through the recess 2', while the slide-wall 3^c 25 is holding the stop-arm member d securely in place. Then, on a further retraction of the slide, to bring the recess 2 in alinement with the shaft-bearing a⁴, the arm-hub d⁴ can be drawn out of said bearing and 30 through said recess 2.

Thus by a simple manipulation of the slide, either one of the members C and d can be released and withdrawn before the other is released; and, by reason of the organization here described, said cross-shaft and stop-lever members will be removable one only at a time. Also, it is evident that the stop-lever is not provided with the cross-shaft, nor is this shaft itself provided with 40 any handle or like device whereby to aid in the removal thereof from the frame; on the contrary, after the cross-shaft is withdrawn, the frame, slide and barrel may be disassembled while said lever d remains assembled on the frame; thus said stop-lever is, in no way involved in the operation of removing the cross-shaft.

Said lever or arm d, as will now be evident, constitutes, when coupled as set forth,—a means, or "handle", whereby the operator may turn the shaft C, and whereby the slide S may be locked in and released from its retracted position. Similarly as described in my said application Serial No. 55 209,485, the lever d is herein shown provided with a slide-lock face, 4^e, and with the inward projection, d², whereby this slide-lock member d may be actuated upwardly by the usual spring-actuated magazine follower, as n, (Figs. 3, 4), and thereby lock

the slide S in retracted position (Fig. 2) whenever the supply of cartridges in the magazine shall become exhausted.

This arrangement will be more clearly understood from the sectional plan view Fig. 4, in which said lever arm d, is shown provided with inward projections d² extending through the opening at f³ of the frame. In this view the inner end of said projection d² is shown in position for engaging 70 with the upper side of the usual follower, as n, of the ordinary magazine, m, of the firearm. Since said follower n is in practice actuated by a. spring, (not shown), when the follower rises upwardly to a point 75 for engaging said inward projection d² thereby the lever-arm d will be spring-actuated in a direction and for the purpose of raising the lock-end or slide-engaging face 4^e of said lever-arm into contact with the 80 lower side of the slide S, so that when the slide is drawn rearwardly to the position indicated in the side view Fig. 2, said face 4^e of the lever-arm will engage the rearward face 3^k of the recess 2, and thus operate 85 in a well-known manner as a slide-stop for holding, or "locking", the slide in said retracted position.

A frictional resistance may be applied (as herein illustrated) to the stop-arm d, 90 by transmitting thereto a resistant force derived from a suitably located spring, preferably from the slide-actuating spring. This spring, N, acting through the barrel B and its depending part, or lug, b', applies 95 a pressure to the cross-shaft C, and thereby tends to restrict the freedom of rotation of this shaft by the amount of the friction so produced and transmitted. When employed in connection with means for securing such a frictional resistance, said stop-arm d and said shaft C being separate members, and neither one comprising the other, are therefore to be provided with some suitable coupling or coacting means whereby these two 100 members may have concurrent rotative movements about their respective axes; the extent of these movements, of course, is determined, in practice, by the required extent of the swinging movement of the stop-arm d. In the present instance, these objects are accomplished by means of the described coupling together in a coacting manner of the members C and d.

The mechanism illustrated in Figs. 14 and 15, corresponds with that of Figs. 1 to 11, excepting as to the form of the coupling means for coactively connecting the shaft C with the hub d⁴ of stop-arm d. Instead of having the extension C⁵, (see Figs. 6, 7), the shaft C is here shown (Figs. 14, 15) provided at the inner end thereof with a transverse key-way space or channel, c⁹, and the hub d⁴ is provided with an extension, d⁹, which fits closely into said space c⁹. 120 125 130

Thus said hub-projection constitutes a shaft-turning actuator or means which is appurtenant to the stop-arm d , and which does not essentially modify the operation of 5 the firearm mechanism, as a whole, nor the assembling or disassembling thereof.

In Figs. 16, 17, a further modification is illustrated, in which the shaft C extends through the frame-bearing a^4 and is provided, outside of the frame, with an extension c^4 similar to the extension c^4 of Figs. 6, 7. The arm d has the hub d^4 thereof fitted upon and carried by said extension c^5 , and cut away at 7 to allow the passage 15 thereby of the slide-wall 3^e ; thus said wall does not, in this particular instance, hold said arm-hub in place. For this latter purpose, the arm d is fitted to engage over the frame-wall f^7 , which engages between faces 20 8 and 9 of the arm,—also against face $8'$,—as clearly indicated in Fig. 16. For coactively engaging with the slide S, the arm d is here shown provided with the lock-face 25 4^e , which (in this instance) is located for engaging with a projection, $3^{k'}$, that is on the slide wall 3^e . By reason of this feature, the aforesaid lock-space or recess, as 2, is or may be omitted in this modification, while retaining all the functions of the 30 stop-arm, and providing for a removal of the shaft C while said arm remains in place on the frame. After the shaft C has been removed, the slide S may then be drawn forwardly on the frame and from over the 35 stop-arm, whereupon this arm may be lifted upwardly out of its said engagement with the frame.

In the form and arrangement of the mechanism which is shown in Figs. 18-20, the 40 shaft C,—while coacting with the stop-lever arm d ,—is not turned in its seats by said lever-arm d . The member C is shown held in place by the transverse face $c^{8'}$ thereof engaging inside of the slide wall 3^e , and by 45 the head c^4 engaging against the outside of the frame, the same as already described in connection with Fig. 5. The larger portion of shaft C, however, extends only through one side of frame F, and through 50 the barrel-lug b' , while the arm-hub d^4 , extends through, or nearly through the frame wall, (Fig. 19), and is bored to receive the cylindrical extension c^5 of said member C. Thus the arm d is journaled by its hub d^4 in the frame seat a^4 , and this shaft-extension c^5 is journaled in the bore of said arm-hub. By this means, the arm d is very effectively guided and controlled, but does not rotate the shaft C. However, 60 the spring N and the recoil, by acting through the barrel as explained, naturally presses the member C forwardly and then backwardly at certain times, so that the extension c^5 presses the hub d^4 in a similar 65 manner and thereby presses said hub against

the surface of the hub-seat a^4 and thereby increases the (otherwise) normal amount of direct friction as between said hub d^4 and the frame. By first suitably locating the slide S, (as already explained in connection 70 with Figs. 3, 4), the shaft C and arm d may be removed either one before the other, or both together, as may be desired.

So far as shown in the principal views, Figs. 1 to 20, inclusive, that portion of the 75 stop-arm which is designated as the "lock-end," is indicated as if it were formed integral or rigidly connected with the main portion of said stop-arm member of the mechanism, but it should be understood that 80 said member may be made of any suitable composite form in which the lock-end is an appurtenant of or to the lever-arm. One suitable arrangement of this character is illustrated in Figs. 21, 22, 22^a, where the 85 shaft C and lever-arm hub, d^4 , are shown of a similar construction as in Figs. 18 and 19, while the lock-end 4^a is pivotally connected at d^{10} with the main lever arm d , this arm being shown extended rearwardly 90 to form the handle portion which thus has the thumb-piece thereof brought well back toward the rearward end of the frame F. Said pivotally-connected lock-end is shown (see Fig. 22) provided with the inward extension d^2 for coactively engaging with the usual magazine follower, as already described, but in this modification, said part 95 4^a is guided in the frame-slot f^3 . One result of this arrangement, evidently is to 100 transmit the forward pressure of the slide-face 3^k in large part through said inward projection d^2 to and against the forward face, f^8 , of said frame-slot, and thus relieve the arm-bearing at a^4 (Fig. 22) of some 105 of the pressure which would otherwise and normally be transmitted thereto. The operation of this composite form of the device is obviously the same as the operation of the integral form thereof hereinbefore described in so far as concerns the invention herein described and claimed, and does not materially modify the functions or coaction of the lever-arm and cross-shaft with 110 relation to each other, or the relations of 115 these combined members to the frame, barrel and slide.

When the stop-arm d , in the arrangement of Figs. 18, 19, and 20, 21, 22, is removed, the shaft C may remain in place, so that no disconnection of the barrel is thereby involved when said shaft constitutes a frame-and-barrel-uniting member. Also, when the shaft C is removed in this arrangement, the arm d , (when this arm is journaled as described in the shaft-bore, or seat), may remain in place and thus serve to hold the slide S in retracted position,—Fig. 2,—during the shaft-removing and shaft-replacing operations. Thus each of said members C 130

and *d* not only may remain in working position while the other is removed, but the one so remaining may continue to perform certain of its functions after the other said member has been withdrawn. However, in some instances the arm *d* need not be separately journaled in the frame, (not herein shown), and therefore would not, in such an instance,—be operable in all respects in the same manner as in the particular arrangements herein described.

In the organization of the mechanism as illustrated in Figs. 1 to 14, inclusive, the shaft *C* and arm *d* are releasably held in their respective working positions by means of faces arranged as follows: one pair of coacting faces formed, respectively, on the shaft and on the side-wall which is opposite to the stop-arm and located in positions for releasably holding said shaft in place; and, another pair of coacting faces formed respectively on the stop-arm and on the side-wall adjacent thereto, and located in positions for releasably holding said stop-arm in working position, said pairs of faces being arranged for permitting said shaft to be withdrawn from one side only of the firearm and said stop-arm to be withdrawn from the other side only of the firearm.

While the stop-arm member, as *d*, is carried on the shaft *C* exteriorly of the frame, the same in Fig. 4 as in Fig. 18, so that said stop-arm member is journaled in the frame by means of a short projecting portion (usually designated as the hub) which extends inwardly from the arm itself and is provided with means for coupling together the arm and shaft in such a manner that the shaft is withdrawable from one side of the frame while the stop-arm is withdrawable from the other side of the frame; and, so that during the operation of withdrawing either said member, the coupling means is automatically uncoupled. Thus either one of the members *C* and *d* may be withdrawn independently of the other said member whether or not the two members are provided with such couplings.

In the constructions illustrated in Figs. 1 to 15, inclusive, the two members, shaft *C* and stop or lever-arm *d* have appurtenant thereto, means for operatively coupling together these members with a driving or shaft-turning connection when assembled together on the frame from opposite sides, respectively, of the frame and slide; and, as already indicated, said members *C* and *d* are shown fitted together and arranged for being assembled together only from opposite sides, respectively, of the frame and firearm, while the shaft-withdrawal is limited to that side only of the firearm, and to that side which is opposite to the side having the lock-face on the slide. In Figs. 17 and 18, however, said shaft and stop-arm

members are shown coupled together in such a manner as to provide for said arm a supportive, but not a shaft-turning connection, since the shaft-extension,—as *C*², Fig. 18,—is fitted to guide and position the arm member while this on being swung up or down, and does not turn the shaft; in each said instance, however, the shaft *C* is journaled in the frame, and is insertible and removable from one side only thereof, while the stop-arm *d* is arranged to be assembled in the mechanism only from the opposite side of the frame.

Having thus described my invention, I claim:

1. In a firearm, in combination, a frame having transversely thereof a shaft-seat; a shaft supported in said shaft-seat, and means for releasably holding said shaft in said shaft-seat, and for limiting the shaft-withdrawal to one side only of the firearm; a stop-arm carried on said shaft and on that side of the firearm which is opposite to said shaft-withdrawal side thereof, and said stop-arm having appurtenant thereto a lock-end in position and operable for coaction with the lock-face of a slide; and, a breech-slide retractable on the frame and provided on the side thereof adjacent to said stop-arm with a lock-face in position for coaction with said lock-end when the slide is in one retracted position.

2. In a firearm, in combination, a frame having transversely thereof a shaft-seat; a shaft supported in said shaft-seat, and means for releasably holding said shaft in said shaft-seat, and for limiting the shaft-withdrawal to one side only of the firearm; a stop-arm carried on said shaft and on that side of the firearm which is opposite to said shaft-withdrawal side thereof, and said stop-arm having appurtenant thereto a lock-end in position and operable for coaction with the lock-face of a slide; a breech-slide retractable on the frame and provided on the side thereof adjacent to said stop-arm with a lock-face in position for coaction with said lock-end when the slide is in one retracted position; means for releasably holding said stop-arm in working position relative to the frame and breech-slide, and arranged for permitting said arm to be withdrawn independently of the withdrawal of the shaft; and, shaft-and-arm-coupling means in position and operable for releasably coupling together the stop-arm and shaft, and for thereby turning the shaft from the movements of the stop-arm when both shaft and stop-arm are in working position.

3. In a firearm of the class described, the combination with a frame and a barrel, of a breech-slide retractably supported on the frame and having depending therefrom two side-walls slidably engaging with the top

- portion of the frame, said slide being provided on one side-wall thereof with a lock-face; and said frame having a shaft-seat transversely positioned therein at the rearward end-portion of the barrel and below said slide; a shaft supported in said shaft-seat and fitted to be withdrawn therefrom only in a direction away from the side-wall having said lock-face; a stop-arm operably supported on the frame in position for coacting with said lock-face when the slide is retracted; and, shaft-turning means appurtenant to the stop-arm.
4. In a firearm of the class described, the combination with a frame and a barrel, of a breech-slide supported on the frame and having two side-walls slidably engaging with the top portion of the frame, said slide being provided on one side-wall thereof with a lock-face and in the opposite side-wall with a shaft-releasing recess, and said frame having a shaft-seat transversely positioned therein at a height partly above and partly below the lower edges of said side-walls; a shaft supported in said shaft-seat and fitted to be withdrawn therefrom only in a direction away from the side-wall having said lock-face and through said shaft-releasing recess; a stop-arm operably supported on the frame in position for coacting with said lock-face when the slide is retracted, and provided with means constituting a shaft-turning connection which is disconnected on and by the withdrawal of said shaft.
5. In a firearm, in combination, a frame having transversely thereof a shaft-seat; a shaft supported in said shaft-seat, and means for releasably holding said shaft in said shaft-seat and for limiting the shaft-withdrawal to one side only of the firearm; a stop-arm carried on said shaft and on that side of the firearm which is opposite to said shaft-withdrawal side thereof, said stop-arm having appurtenant thereto a lock-end in position and operable for coaction with the lock-face of a slide; a breech-slide retractable on the frame and provided on the side thereof adjacent to said lock-end, a stop-arm with a lock-face in position for coaction with said lock-end when the slide is in one retracted position; and, a pair of coacting faces formed respectively on the stop-arm and on the slide-wall adjacent thereto, in positions for releasably holding said stop-arm in working position relative to the frame and breech-slide, and arranged for permitting said stop-arm to be withdrawn independently of said shaft-withdrawal.
6. In a firearm, in combination, a frame having transversely thereof a shaft-seat; a shaft supported in said shaft-seat, and having means for releasably coupling said shaft with a stop-arm; a stop-arm formed separately from and carried on said shaft ex-

teriorly of the frame, and having a lock-end in position and operable for coaction with the lock-face of a slide; and, a breech-slide retractable on the frame through a loading stroke from a firing to a loading position and provided on the side thereof adjacent to said stop-arm with a lock-face in position for coaction with said lock-end when the slide is in one retracted position, and provided on the side thereof opposite to said lock-face with means for releasably holding said shaft in said shaft-seat.

7. In a firearm, the combination with a frame and with a barrel, of a breech-slide retractably supported on the frame and having on one side thereof a lock-face, the frame and the rearward end of the barrel having interlock portions provided transversely with alined seats which together form a shaft-seat extending through the frame; a cross-shaft having the body portion thereof disposed in said shaft-seat and removable therefrom only in a direction away from said lock-face; means appurtenant to said slide for releasably retaining the cross-shaft in said shaft-seat; and, a stop-arm coactive with said lock-face and with said shaft, and journaled in the firearm at that end of said shaft-seat which is opposite to the shaft-withdrawal side of the frame.

8. In a firearm, the combination with a frame and with a barrel, of a breech-slide retractably supported on the frame and having on one side thereof a lock-face, the frame and the rearward end of the barrel having interlock portions provided transversely with alined seats which together form a shaft-seat extending through the frame; a cross-shaft having the body portion thereof disposed in said shaft-seat and removable therefrom only in a direction away from said lock-face; means appurtenant to said slide for releasably retaining the cross-shaft in said shaft-seat; a stop-arm having a hub-portion journaled in that end of said shaft-seat which is on the same side of the firearm as said lock-face, and having appurtenant thereto a face in position for coacting with said lock-face of the slide; and, shaft-and-arm coupling means appurtenant to the shaft.

9. In a firearm, the combination with a frame and with a barrel, of a breech-slide retractably supported on the frame and having on one side thereof a depending side-wall provided with a shaft-retaining face, and having on the other side thereof a lock-face, and the frame and the rearward end of the barrel having interlock portions provided transversely with alined cross-shaft seats which together extend through the frame and are positioned in the frame at a height partly above and partly below the plane of the lower edges of said shaft-retaining face; a cross-shaft having the body

portion thereof rotatably disposed in said alined seats of the frame and barrel and having a transverse face coactive with said shaft-retaining face, thereby normally to 5 prevent a longitudinal withdrawal of the cross-shaft, said shaft-retaining face having the continuity thereof interrupted at a position for permitting the withdrawal of the body of the cross-shaft outwardly from 10 said seats when the slide is in one position thereof; and, a stop-arm journaled in said shaft-seat at the end thereof which is opposite to the slide-wall having said shaft-retaining face, the stop-arm being coactively 15 connected with said shaft, and being also provided with a face in position for coaction with said lock-face of the slide.

10. In a firearm, the combination with a frame and with a barrel, of a breech-slide 20 retractably supported on the frame and having on one side thereof a depending side-wall provided with a shaft-retaining face, and having on the other side thereof a lock-face, and the frame and the rearward end 25 of the barrel having interlock portions provided transversely with alined cross-shaft seats which together extend through the frame and are positioned in the frame at a height partly above and partly below the 30 plane of the lower edges of said shaft-retaining face; a cross-shaft having the body portion thereof rotatably disposed in said alined seats of the frame and barrel and having a transverse face coactive with said 35 shaft-retaining face, thereby normally to prevent a longitudinal withdrawal of the cross-shaft, said shaft-retaining face having the continuity thereof interrupted at a position for permitting the withdrawal of the 40 body of the cross-shaft outwardly from said seats when the slide is in one position thereof; a stop-arm having a hub-portion journaled in said shaft-seat at the end thereof which is opposite to the slide-wall having 45 said shaft-retaining face, the stop-arm having appurtenant thereto a face in position for coacting with said lock-face of the slide; and, shaft-turning coupling means appurtenant to the stop-arm and said shaft.

50 11. In a firearm, the combination with a frame and with a barrel, of a slide having on one side thereof a lock-face and retractably supported on the frame, said frame and barrel each having near the rearward end 55 of the barrel, interlock portions provided transversely with cross-shaft seats which are cylindrical and alined; a barrel and frame uniting cross-shaft having a cylindrical body portion thereof disposed in said alined 60 seats, and also having on said body portion thereof, a transverse bearing face; shaft-retaining means appurtenant to that side of the slide which is opposite to said lock-face and in position and arranged for coaction 65 with said transverse bearing face of the

cross-shaft to thereby hold the cross-shaft from withdrawal during one portion of the retraction of the slide, and for withdrawing from such coaction in one position of the slide; a lever-arm formed separate from and 70 having a coupling connection with said cross-shaft, and supported in a position for being swung into engagement with said lock-face when the slide is in a retracted position; and, a spring in position and connected for applying friction to said body portion of the shaft.

12. In a firearm, the combination with a frame and with a barrel, of a slide having on one side thereof a lock-face and retractably supported on the frame, said frame and barrel each having near the rearward end of the barrel, interlock portions provided transversely with cross-shaft seats which are cylindrical and alined; a barrel 80 and frame uniting cross-shaft having a cylindrical body portion thereof disposed in said alined seats, and also having on said body portion thereof, a transverse bearing face; shaft-retaining means appurtenant to 85 that side of the slide which is opposite to said lock-face, and in position and arranged for coaction with said transverse face of the cross-shaft to thereby hold the cross-shaft from withdrawal during one portion 90 of the retraction of the slide, and for withdrawing from such coaction in one position of the slide; a lever-arm formed separate from and carried by said cross-shaft on that 95 side of the frame which is opposite to said shaft-retaining means, and in a position for being swung into engagement with said lock-face when the slide is in a retracted position; a spring in position and connected 100 for applying a frictional resistance to the shaft; and, coupling means appurtenant to the shaft and lever-arm and arranged for transmitting said frictional resistance to the lever-arm.

13. In a firearm, the combination with a frame having transversely therein a cross-shaft seat and also provided with a magazine having an actuated follower, of a barrel supported at the rearward end thereof on the frame; a bolt-carrier slidable on the 110 frame and on one side thereof provided with a shaft-retaining side-wall engaging over one side of the frame, and on the opposite side thereof having a lock-face, said cross-shaft seat being positioned in the 115 frame at a height partly above and partly below the plane of the lower edge of said shaft-retaining side-wall of the slide; a cross-shaft having the body portion thereof disposed and fitted to turn in said shaft-seat of the frame and provided with a transverse surface in position for engagement with the shaft-retaining side-wall thereby 120 normally to hold the cross-shaft in working position in said shaft-seat, and said side- 125 wall having a transverse surface in position for engagement with the shaft-retaining side-wall thereby normally to hold the cross-shaft in working position in said shaft-seat, and said side- 130

wall having therein a gate-way space in a position for permitting the withdrawal of the body of said shaft outwardly through said space when the slide is in one position 5 thereof; a slide-locking arm formed separately from and carried by said shaft exteriorly of the frame, and on that side of the firearm which is opposite to said shaft-retaining side-wall, and actuatable by the 10 magazine follower into engagement with said lock-face when the slide is in one position thereof; means for releasably holding the slide-locking arm in working position; and, shaft-turning means appurtenant to the 15 slide-locking arm.

14. In a firearm, in combination, a frame having transversely thereof a shaft-seat; a shaft supported in said shaft-seat, and means for releasably holding said shaft in 20 said shaft-seat; a stop-arm member formed separate from and carried on said shaft exteriorly of the frame, and having a lock-end in position and operable for coacting with the lock-face of a slide; a breech-slide retractable on the frame through a loading stroke and provided on the side thereof adjacent to said stop-arm with a lock-face in position for coaction with said lock-end when the slide is in one retracted 25 position, said shaft-seat being positioned in the frame at a height partly above and partly below the lower edge of that side of the slide which is adjacent to the stop-arm and said slide being also provided on the 30 side thereof adjacent to said stop-arm with a stop-arm-engaging face having therein a shaft-releasing recess constituting a gateway space through which the stop-arm member may be withdrawn away from the shaft.

15. In a firearm of the class described, the combination with a frame and a barrel, of a breech-slide supported on the frame and having two side-walls slidably engaging with the top portion of the frame, said slide 40 being retractable through a loading stroke from a firing to a loading position, and being provided on one side-wall thereof with a lock-face, and said frame having a shaft-seat transversely positioned therein at a height partly above and partly below the lower edges of said side-walls; a shaft supported in said shaft-seat and fitted to be withdrawn therefrom only in a direction 45 away from the side-wall having said lock-face; a stop-arm operably supported on the frame in position for coacting with said lock-face when the slide is retracted, and fitted for having a coupling connection with 50 said shaft when this member is in working

position; one pair of coacting faces formed, 60 respectively, on the shaft and on one of the two side-walls, and arranged for releasably holding said shaft in working position, and another pair of coacting faces formed respectively on the stop-arm and on the other 65 of said side-walls, and arranged for releasably holding said stop-arm in working position, whereby said shaft is withdrawable from one side of the firearm and said stop-arm is withdrawable from the other side of 70 the firearm, each said withdrawal being independent of the other.

16. In a firearm, in combination, a frame having transversely thereof a shaft-seat; a shaft supported in said shaft-seat, and 75 means for releasably holding said shaft in said shaft-seat; a stop-arm carried on said shaft and in a position exteriorly of the frame, and having a lock-end in position and operable for coacting with the lock-face of a slide; a breech-slide retractable on the frame through a loading stroke and provided on the side thereof adjacent to said stop-arm with a lock-face in position for coaction with said lock-end when the slide is 80 in one retracted position, said shaft and stop-arm being fitted and arranged for being assembled together only from opposite sides, respectively, of the frame; and means for operatively coupling the shaft and stop-arm when these members are assembled together on the frame.

17. In a firearm of the class described, the combination with a frame, a barrel, and a breech-slide having a lock-face, of a combined barrel-and-frame-uniting cross-shaft and slide-locking stop-arm, comprising a barrel-and-frame-uniting shaft journaled in the frame and barrel and insertible and removable from one side only of the frame, 95 and a stop-arm in position for coacting with said lock-face of the slide and arranged to be assembled from the other side only of the frame; means for releasably and separately retaining in working position said shaft and stop-arm, and for permitting each to be disassembled from the firearm independently of the other; and, means appurtenant to the shaft and stop-arm for coupling together these members with a shaft-turning connection when said members are assembled together from the opposite sides, respectively, 100 of the frame.
